(57) **CLAIM**

The ornamental design for a tapering candle with a plurality of vertical cuts that run through the candle, as shown and described.

DESCRIPTION

FIG. 1 is a top and front perspective view of a first embodiment of a tapering candle with a plurality of vertical cuts that run through the candle showing the new design.

FIG. 2 is a top plan view of the first embodiment of the tapering candle with a plurality of vertical cuts that run through the candle of FIG. 1.

FIG. 3 is a front elevation view of the first embodiment of the tapering candle with a plurality of vertical cuts that run through the candle of FIG. 1, the rear elevation view being a mirror image.

FIG. 4 is a left side elevation view of the first embodiment of the tapering candle with a plurality of vertical cuts that run through the candle of FIG. 1, the right side elevation view being a mirror image; and,

FIG. 5 is a bottom plan view of the first embodiment of the tapering candle with a plurality of vertical cuts that run through the candle of FIG. 1.

FIG. 6 is a top and rear perspective view of a second embodiment of a tapering candle with a plurality of vertical cuts that run through the candle showing the new design.

FIG. 7 is a top plan view of the second embodiment of the tapering candle with a plurality of vertical cuts that run through the candle of FIG. 6.

FIG. 8 is a front elevation view of the second embodiment of the tapering candle with a plurality of vertical cuts that run through the candle of FIG. 6, the rear elevation view being a mirror image.

FIG. 9 is a left side elevation view of the second embodiment of the tapering candle with a plurality of vertical cuts that run through the candle of FIG. 6; and,

FIG. 10 is a bottom plan view of the second embodiment of the tapering candle with a plurality of vertical cuts that run through the candle of FIG. 6.

Any portion of the tapering candle with a plurality of vertical cuts that run through the candle shown in broken lines is for the purpose of illustrating environmental structure and forms no part of the claimed design.

The dot-dash-dot lines shown in the drawings define the boundary of the claim and form no part of the claimed design.
